UNITED STATES PATENT OFFICE.

WALTER JACOB WOHLENBERG, OF BOZEMAN, MONTANA.

FLUID-METER.

1,303,425.

Specification of Letters Patent. Patented May 13, 1919.

Application filed October 22, 1917. Serial No. 197,997.

To all whom it may concern:

Be it known that I, WALTER JACOB WOHLENBERG, a citizen of the United States, and a resident of Bozeman, in the county of Gallatin and State of Montana, have invented a new and Improved Fluid-Meter, of which the following is a full, clear, and exact description.

My invention relates to any meters for indicating, registering or recording the densities, pressures and temperatures of any fluids and for indicating, registering or recording the quantities of fluid flow and in such it is a special form of the application 10 of the device claimed in my last application for fluid meters, Serial Number 198,895. The same nomenclature is used in this application as in the above mentioned application to denote parts performing similar 15 functions.

An object of my invention is to have the means of so varying the inclination of the density chamber that the levels of the sealing liquid surfaces in the density cell and 20 density cylinder will be maintained the same, thereby causing the exact external fluid pressure to be exerted by the sealing liquid on the density fluid.

A second object of my invention is to have 25 the means of automatically so varying the inclination of the density chamber that the levels of the sealing liquid surfaces in the density cell and density cylinder will be maintained the same, thereby causing the exact external fluid pressure to be exerted by the sealing liquid on the density fluid.

A third object of my invention is to have 30 the varying of the inclination of the density chamber, caused by the density variation of the external fluid, be the means of indicating the variation of density, pressure and 35 temperature of said external fluid.

A fourth object of my invention is to have 40 the said variation of inclination of the density chamber be used as a means of correcting the rate of registering the fluid flow in a conduit to the rate of weight flow of the said fluid.

I accomplish these and other objects of 45 my invention by the structures conventionally disclosed in the accompanying drawings, in which similar characters of reference denote corresponding parts in all views shown.

Figure 1 is a sectional view of the arrangement disclosing the principal features 50 of the invention.

Fig. 2 is a view of the arrangement shown in Fig. 1, looking in the direction of arrows from the line A—A.

Fig. 3 is a longitudinal view of the arrangement wherein the expansion of the sealing liquid is compensated for by the addition of the compensating cylinder or tube.

Fig. 4 is a plan view of the arrangement 55 shown in Fig. 3.

Fig. 5 is a view of the same arrangement, now looking in the direction of arrows from the line C—C.

Fig. 6 shows an arrangement wherein the zero positions and the magnitude pointers 70 and scale deflections can be adjusted independently of the quantities of fluid within the density cell and independently of the quantity of sealing liquid contained in it.

Referring now to Figs. 1 and 2, the density chamber is represented by the tubular ring 1, supported by means of arms 8 on the axis 9, which is free to rotate in the bearings of supports 12 and 15. This tubular ring is of uniform section, having however, a small section cut out at 2 so that its one end is open to the surrounding fluid. In order to retain the balance of the ring about its center, a small shoulder as (a) may be added at the open end of the tube. Its other 80 end is closed as shown at (b). The ring having its center of gravity coincident with the geometric center or axis will remain in any angular position in which it may happen to stop.

In the space 3 adjacent the closed end (b) is contained the density fluid which in general may be any elastic fluid. In the special cases in which the mechanism is to respond accurately to the variations of density of 95 the surrounding fluid, this density fluid will be of the same kind as the surrounding fluid. This fluid is sealed in by means of the sealing liquid 4 which fills the bottom part of the ring from the level 5 on the one side to 100 the same level 6 on the other side. The space 3 thus really forms the density cell as described in the above mentioned application, and the density cylinder is the part of the ring in the vicinity of the other surface 6 of the sealing liquid.

Suppose now that the surrounding fluid pressure should increase thus forcing the sealing liquid 4 farther into the density cell 3. Obviously, if the tube remained stationary the level of the sealing liquid 5 would now be raised above its level 6, and conse-

quently, the center of gravity of the column of sealing liquid would be an amount Δh from the point p to a point p' . In other words, the center of gravity of the whole 5 tube system would be raised so that a turning moment w^1 would exist about the axis of shaft 9. But the ring is free to turn about this axis, whence it will turn to that 10 position in which p' comes directly below 9, where the turning moment vanishes and the sealing liquid surfaces will again be at the level. In this position, the pressure existing 15 in the density cell will be exactly equal to that existing in the surrounding medium. 15 The activity is more exactly described as follows: As the surrounding pressure increases there will be an excess on the surface 6 over that existing on the surface 5, due to the density fluid and there will be 20 an excess on the outside of surface b over that existing on the inside of this surface due to the density fluid pressure. The excess external pressure will thus tend to force the surface b down and the surface 5 up 25 until the pressure in 3 equals the external pressure minus the head due to the difference in level of surfaces 5 and 6. If now, for an instance, the level 5 is forced above the level 6, then certainly the pressure on the top of 30 surface b will still be greater than that on its bottom surface and consequently, as the inertia of the ring is overcome, this excess of pressure will force this surface down and the level of surface 5 will sink, and when 35 equilibrium is established, the surface 5 will be at the same level as 6, and the pressure within space 3 will equal that on the outside. If now the external pressure decreases, then obviously the excess of pressure 40 in the lower side of b will tend to force this surface away from the level 5 and the level 6 above the level 5. Again, when equilibrium is established, the levels of 5 and 6 will be the same and the pressure 45 within space 3 will equal the external pressure.

The angular displacement of the ring can be adapted to indicate the variation of density of the surrounding fluid by means of a 50 pointer 10 fixed to the axis 9, and sweeping across a dial 11, fixed by means of arms 13 and 14, as shown. This dial may be graduated in terms of the density of the surrounding fluid. For saturated vapors there 55 is a definite density and temperature for each pressure. For these it may thus be likewise graduated to read directly their pressures and temperatures.

If now the sealing liquid has a considerable 60 volume variation with temperature, then for two different temperatures there will be a considerable difference in the length of the column of sealing liquid. This of itself, would operate, even for the same 65 density cell volume, to cause the ring to

undergo an angular deflection. If now the scale 11 could be so arranged as to undergo from such causes exactly the same angular deflection as the ring 1, then obviously, the relative position between pointer 10 and the 70 scale will be unaffected by these volume variations of the sealing liquid and the deflection of the pointer with respect to the scale will be wholly caused by volume variations of the density fluid. This is accomplished 75 by the mechanism disclosed in Figs. 3, 4 and 5.

In this arrangement, the ring 1 with pointer 10 is deflected angularly just as before described. The scale 11 however, is 80 now replaced by scale 26, which is fastened by means of arms 25 to the compensating ring 20. This ring is constructed and mounted exactly similarly to the ring 1. The dial 26 may extend about the whole 85 circumference, or may, as shown, extend only partially around and leave its weight balanced by a weight W attached diametrically opposite it. The space 3' now has a definite wall or partition 6' at its lower 90 level, or the closed end b' of the ring may be revolved into the position 6'. Between this wall or the partition 6' and the adjacent compensating liquid surface, there exists a vacuum so that the excess external fluid 95 pressure on the wall or partition will tend to force the ring around until the partition or wall is in contact with the said surface of the liquid column. This partition is so located that at a definite temperature 100 the columns of sealing liquid in both the density and compensating rings have the same length and are at the same levels. These rings will in general be of the same 105 diameter, although this is not necessary, it being only necessary that they be circularly concentrically symmetrical, and that the dial 26 has the same diameter as that of the circle described by the pointer 10. In other words, it is only necessary that at a given temperature, the angle subtended by the sealing and compensating liquid column arcs are equal. Then for a given variation of temperature, each arc will lengthen by the same number of degrees, and consequently, the tubular rings will be turned through the same number of degrees in bringing the centers of gravities of the two columns directly below the axes of supports 9 and 18. In this position the surfaces 5 and 5' of the 110 columns will be respectively at the same levels as the surfaces 6 and 6' at the other extremities.

Furthermore, the compensating ring is so set as to have the wall 6' on the same side of the axes 9 and 18 as is the surface 6 of the sealing liquid in the density ring. Suppose now that there is a variation in the length of the columns 4 and 4' of the sealing and compensating liquids. It is ob- 115 120 125 130

vious that the ring 1 as shown in Figs. 3, 4 and 5 will be deflected in the clockwise direction in bringing the surfaces 5 and 6 to the same level. Similarly, the ring 20 will 5 be turned about its axis 18 in the clockwise direction. If now the liquid column arcs are circularly concentrically symmetrical, as above described, then obviously the rings will be deflected by equal angular amounts 10 in the same direction by the variations of length of said columns from temperature variations. The scale 26 supported by arms 25 to the ring 20 will thus move exactly with the pointer 10 in deflections caused by 15 volume variations of the sealing and compensating liquids and the relative deflection will be an indication of the variation of volume only of the density fluid.

The deflection of the compensating ring 20 is obviously an indication of the temperature variation of the surrounding medium. It may thus, by means of pointer 26 fixed to the compensating ring, be adapted to indicate the temperature on a stationary dial 24 fixed 25 by means of arm 23.

The dial 26 may be graduated to indicate both pressure and density as shown in Fig. 5, and the dial 24 to indicate the temperature. In this arrangement lines 39 are 30 constant temperature lines and lines 38 constant pressure lines. Graduations 40 are for density indications and graduations 41 for temperature indications. The density is read directly from the graduation 40 opposite 35 the pointer 10, and the temperature is read directly from the graduation opposite the pointer 27. To read the pressure follow the line 39 marked with the same temperature as that indicated by pointer 27 to its 40 intersection with the projection of the pointer 10 on the dial. The constant pressure line 38 passing through this point of intersection indicates the pressure of the surrounding fluid at the instant of consideration.

To apply this mechanism in fluid meters measuring the quantity of fluid flow it is merely necessary to attach to the axes 9 and 18 disks as 16 and 21 with pins 17 and 22 50 from which the angular deflection may be transmitted by connecting rods as 33 and 28 to levers 30 and 35 through pins 34 and 29. The lever 30 has a fulcrum at 31 so that its other end transmits motion to the floating 55 lever 35 through pin 32 in the opposed direction to that of the pin 22. There will now, as in the lever 51 of the application filed November 1, 1916, be a point 36 of the lever 35 whose displacements will be proportional 60 to the volume variation of the density fluid. At this point a rod 37 may be attached to transmit the displacements to the flow registering mechanism, thereby correcting the rate of registering to the rate of weight flow 65 of the fluid.

In the special arrangement disclosed in Fig. 6 the deflections of ring 1 are transmitted through axis 9 and the lever 10' to the rod 58 and the deflections of ring 20 through the arm 42 to the rod 45. These rods 70 transmit the respective deflections to the pointer 60 and the arm 49 carrying the dial 26'. The weight W' and W'' are for the purposes merely of wholly or partially balancing the parts at the other end of the arms 75 to which they are attached.

The magnitudes of the deflections of the dial 26' with respect to the deflections of ring 20 may be adjusted by means of changing the position of the connection of arms 47 80 on the arm 49 or by changing the position of the connection at 44 on arm 42. The zero position of this dial may be adjusted by means of the turnbuckle 46 which is adapted to change the length between the connections 48 and 44.

Similarly the magnitudes of deflection of the pointer 60 may be adjusted by varying the connection positions 59 or 53 to other points as 61 or 55, and the zero position of 90 the pointer may be adjusted by means of turnbuckle 57. This arrangement thus gives a means of adjusting the magnitudes of the deflections independently of the quantity of fluid contained within the density cell. 95

For the application as a gage measuring pressures and temperatures, it is obvious that the fluid contained within the density cell need not necessarily be of the same kind as the surrounding fluid for a scale graduated 100 as illustrated in Fig. 5 affords the means of determining the pressure and temperature relations for a given density fluid for any surrounding fluid medium whatsoever. For instance, having read the temperature from 105 the indicator on dial 24 of pointer 27, then corresponding to this temperature there can be only one pressure for each position of the pointer 10 with respect to the dial 26 irrespectively of what external fluid pressure is 110 maintaining the pointer in such a position. For such an application of the meter however, the position of the pointer 10 with respect to the graduations 40 will not in general be an accurate indication of the density of 115 the surrounding fluid medium. It will be an indication of the density of the fluid within the density cell, and when the temperature is known from the indication on dial 24 then obviously the pressure at which this density 120 fluid must be existing is accurately indicated by the pointer 10 with respect to the constant pressure lines 38. But this pressure is equal to the external fluid pressure.

For the mere purpose of indicating pressures, temperatures and densities, it is now not necessary that the variation of angular position of the rings 1 and 20 be automatic. For instance, if it is found desirable for the sake of cheapness, or for other reasons, to 130

use a comparatively light weight sealing liquid, then these rings might be turned by hand to the position in which the surfaces 5 and 5' will be respectively at the same levels 5 and the surfaces 6 and 6'. In this new position the pointers will accurately indicate the pressures, temperatures, and in special cases, also the densities of the surrounding fluid. To gage the levels of the aforementioned surfaces, a horizontal string or edge s—s may be adapted to be brought in the proximity of these surfaces and then the rings turned by hand until they are at the same levels. For such an arrangement it would of course 10 be necessary to have the rings made of a transparent material.

It is further obvious, that many changes, other than those shown, may be made in the arrangement and construction of this apparatus without departing from the spirit and scope of the invention, and therefore, I 20 do not wish to limit my invention to the exact arrangements or constructions shown.

Having thus described my invention, I 25 claim as new and desire to secure by Letters Patent;—

1. In meters, a casing adapted to be placed in a fluid whose properties are to be measured, said casing being suspended from an 30 axis about which it is rotatable, said casing inclosing within it the density chamber closed at one end and having an opening to the surrounding fluid, said casing inclosing a space having an intermediate portion at 35 the lowest gravity level, said casing containing a sealing fluid and also containing a density fluid in the space adjacent the closed end, said density fluid being confined to this space by the sealing liquid as and for the 40 purpose set forth.

2. In meters, a casing adapted to be placed in a fluid whose properties are to be measured, said casing being suspended from an axis about which it is rotatable, said casing 45 inclosing within it the density chamber closed at one end and having an opening to the surrounding fluid, said casing inclosing a space having an intermediate portion at the lowest gravity level, said casing containing a sealing fluid and also containing a density fluid in the space adjacent the closed end, said density fluid being confined to this space by the sealing liquid, said sealing liquid having a greater density than 55 the surrounding and density fluids, as and for the purpose set forth.

3. In meters, a casing adapted to be placed in a fluid whose properties are to be measured, said casing being suspended from an axis about which it is rotatable, said axis 60 of suspension containing the center of gravity of the casing, said casing inclosing within it the density chamber closed at one end and having an opening to the surrounding fluid, said casing inclosing a space having 65

an intermediate portion at the lowest gravity level, said casing containing a sealing fluid and also containing a density fluid in the space adjacent the closed end, said density fluid being confined to this space by the sealing liquid, as and for the purpose set forth. 70

4. In meters, a casing adapted to be placed in a fluid whose properties are to be measured, said casing being suspended from an axis about which it is rotatable, said axis of 75 suspension containing the center of gravity of the casing, said casing being geometrically symmetrical with respect to the axis of suspension, said casing inclosing within it the density chamber closed at one end and having an opening to the surrounding fluid, said casing inclosing a space having an intermediate portion at the lowest gravity level, said casing containing a sealing fluid and also containing a density fluid in the space adjacent the closed end, said density fluid being confined to this space by the sealing liquid, said sealing liquid having a greater density than the surrounding and density fluids as and for the purpose set 80 forth. 85

5. In meters, a casing adapted to be placed in a fluid whose properties are to be measured, said casing being suspended from an axis through its center of gravity about 95 which it is rotatable, said casing being in the form of a tubular ring, said tubular ring inclosing within it the density chamber closed at one end and having an opening to the surrounding fluid, said casing inclosing a space 100 having an intermediate portion at the lowest gravity level, said casing containing a sealing fluid and also containing a density fluid in the space adjacent the closed end, said density fluid being confined to this space by the sealing liquid, as and for the purpose set forth. 105

6. In meters, a casing adapted to be placed in a fluid whose properties are to be measured, said casing being suspended from a horizontal axis through its center of gravity about which it is rotatable, said casing being in the form of a tubular ring, said tubular ring being suspended by the horizontal axis in a vertical plane, said tubular ring inclosing within it the density chamber closed at one end and having an opening to the surrounding fluid, said casing inclosing a space having an intermediate portion at the lowest gravity level, said casing containing a sealing fluid and also containing a density fluid in the space adjacent the closed end, said density fluid being confined to this space by the sealing liquid, as and for the purpose set 110 forth. 115

7. In meters, a casing adapted to be placed in a fluid whose properties are to be measured, said casing being suspended from an axis about which it is rotatable, said casing inclosing within it a chamber closed at one end, 120 125

said casing inclosing a space having an intermediate portion at the lowest gravity level, said casing containing a liquid in the space adjacent the closed end, said liquid column varying in length with its temperature and filling the space bounded by the part of the casing extending from its closed end to a surface of said liquid column free to move relative to the casing when the volume of said liquid column varies, as and for the purpose set forth.

8. In meters, a casing adapted to be placed in a fluid whose properties are to be measured, said casing being suspended from an axis about which it is rotatable, said casing inclosing within it a chamber closed at one end, and having an opening to the surrounding fluid, said casing inclosing a space having an intermediate portion at the lowest gravity level, said casing containing a heavy liquid in the space adjacent the closed end, said liquid column varying in length with its temperature and filling the space bounded by the part of the casing extending from its closed end to a surface of said liquid column free to move relative to the casing when the volume of said liquid column varies, as and for the purpose set forth.

9. In meters, a casing adapted to be placed in a fluid whose properties are to be measured, said casing being suspended from an axis through its center of gravity about which it is rotatable, said casing being geometrically symmetrical about said axis, said casing inclosing within it a chamber closed at one end, said casing inclosing a space having an intermediate portion at the lowest gravity level, said casing containing a heavy liquid in the space adjacent the closed end, said liquid column filling the space bounded by the part of the casing extending from its closed end to a surface of said liquid column free to move relative to the casing when the volume of said liquid column varies, as and for the purpose set forth.

10. In meters, a casing adapted to be placed in a fluid whose properties are to be measured, said casing being suspended from an axis through its center of gravity about which it is rotatable, said casing being in the form of a tubular ring, said casing inclosing within it a chamber closed at one end, said casing inclosing a space having an intermediate portion at the lowest gravity level, said casing containing a heavy liquid in the space adjacent the closed end, said liquid column filling the space bounded by the part of the casing extending from its closed end to a surface of said liquid column free to move relative to the casing when the volume of said liquid column varies, as and for the purpose set forth.

11. In meters, a casing adapted to be placed in a fluid whose properties are to be measured, said casing being suspended from

a horizontal axis through its center of gravity about which it is rotatable, said casing being in the form of a tubular ring, said tubular ring being suspended by the horizontal axis in a vertical plane, said casing inclosing within it a chamber, closed at one end and having an opening to the surrounding fluid, said casing inclosing a space having an intermediate portion at the lowest gravity level, said casing containing a liquid in the space adjacent the closed end, said liquid column filling the space bounded by the part of the casing extending from its closed end to a surface of said liquid column free to move relative to the casing when the volume of said liquid column varies, as and for the purpose set forth.

12. In meters, the combination of two casings, adapted to be placed in a fluid whose properties are to be measured, said casings being suspended from axes about which they are independently rotatable, one of said casings, called hereinafter the "density casing," inclosing within it the density chamber closed at one end, said casing inclosing a space having an intermediate portion at the lowest gravity level, said casing containing a sealing liquid and also containing a density fluid in the space adjacent the closed end, said density fluid being confined to this space by the sealing liquid, the other of said casings, called hereinafter the "compensating casing," inclosing within it a chamber closed at one end, said casing being disposed from the closed end, first, longitudinally in a direction of decreasing gravity levels and then longitudinally in a direction of increasing gravity levels, said casing containing a liquid in the space adjacent the closed end, said liquid column, filling the space bounded by the part of the casing extending from its closed end to a surface of said liquid column free to move relative to the casing when the volume of said liquid column varies, as and for the purpose set forth.

13. In meters, the combination of density and compensating casings adapted to be placed in a fluid whose properties are to be measured, said casings being suspended from axes through their centers of gravity, and about which they are independently rotatable, said axes being in line, the density casing inclosing within it the density chamber, closed at one end and having an opening to the surrounding fluid, said casing inclosing a space having an intermediate portion at the lowest gravity level, said casing containing a sealing liquid and also containing a density fluid in the space adjacent the closed end, said density fluid being confined to this space by the sealing liquid, the compensating casing inclosing within it a chamber closed at one end and having an opening to the surrounding fluid, said casing

- being disposed from the closed end, first, longitudinally in a direction of decreasing gravity levels and then longitudinally in a direction of increasing gravity levels, said 5 casing containing a liquid in the space adjacent the closed end, said liquid column varying in length with its temperature and filling the space bounded by the part of the casing extending from its closed end to a 10 surface of said liquid column free to move relative to the casing when the volume of said liquid column varies, as and for the purpose set forth.
14. In meters, the combination of density 15 and compensating casings adapted to be placed in a fluid whose properties are to be measured, said casings being suspended from axes through their centers of gravity, and about which they are rotatable, said 20 density casing being in the form of a tubular ring, said tubular ring inclosing within it the density chamber closed at one end and having an opening to the surrounding fluid, said casing inclosing a space having 25 an intermediate portion at the lowest gravity level, said casing containing a sealing liquid and also containing a density fluid in the space adjacent the closed end, said density fluid being confined to this space by a more 30 dense sealing liquid, said compensating casing being in the form of a tubular ring, said casing inclosing within it a chamber closed at one end and having an opening to the surrounding fluid, said casing being 35 disposed from the closed end, first, longitudinally in a direction of decreasing gravity levels and then longitudinally in a direction of increasing gravity levels, said casing containing a liquid in the space adjacent the 40 closed end, said liquid column varying in length with its temperature and filling the space bounded by the part of the casing extending from its closed end to a surface of said liquid column free to move relative to
- the casing when the volume of said liquid 45 column varies as and for the purpose set forth.
15. In meters, the combination of density and compensating casings adapted to be placed in a fluid whose properties are to be 50 measured, said casings being suspended from horizontal axes through their centers of gravity, and about which they are rotatable, said axes being in line, said density casing being in the form of a tubular ring, said 55 tubular ring inclosing within it the density chamber closed at one end and having an opening to the surrounding fluid, said casing inclosing a space having an intermediate portion at the lowest gravity level, 60 said casing containing a sealing liquid and also containing a density fluid in the space adjacent the closed end, said density fluid being confined to this space by the sealing liquid, said compensating casing being in 65 the form of a tubular ring, said casing inclosing within it a chamber closed at one end and having an opening to the surrounding fluid, said casing being disposed from the closed end, first, longitudinally in a direction of decreasing gravity levels and then 70 longitudinally in a direction of increasing gravity levels, said casing containing a liquid in the space adjacent the closed end, said liquid column varying in length with its temperature and filling the space bounded by the part of the casing extending from 75 its closed end to a surface of said liquid column free to move relative to the casing when the volume of said liquid column 80 varies, as and for the purpose set forth.
- In testimony whereof, I have signed my name to this specification in the presence of two subscribing witnesses.
